[57] CLAIM

The ornamental design for a portion of a make-up planner, as shown and described.

DESCRIPTION

FIG. 1 is a perspective view of a portion of a make-up planner with an insert showing my new design; FIG. 2 is a right side elevational view of the insert for the portion of a make-up planner of FIG. 1;
